ELECTRON DISCHARGE TUBES WITH SPHERICAL CONCENTRIC ELECTRODES

Pierre Patriarche, Paris, France, assignor to Societe Francaise Radio Electrique, a corporation of France

Application March 6, 1947, Serial No. 732,736
In France February 22, 1946Section 1, Public Law 690, August 8, 1946
Patent expires February 22, 1966

9 Claims. (Cl. 250—27.5)

1

In discharge tubes it is essential for the electron stream emitted by the cathode to have the optimum spatial distribution such that the anode, as well as the intermediate electrodes, can operate under the most efficient conditions. Such distribution obviously, is conditioned by the shape of the cathode element which generates the electrons, but it is, also, independent of the shape of the other electrodes and, in particular, of the shape of the anode which is subjected to the electronic bombardment.

Now, the standard shape for the anode is either a cylinder of revolution or, more often, a right angled parallelepiped with more or less flat faces and with more or less rounded edges all according to the shape or the construction of the cathode, which is generally located in the central region of the tube. On the other hand, for technical reasons associated with the closing process the glass bulb which limits the space enveloped by the tube has to be a body of revolution and, owing to this fact, cannot follow the shape of the anode.

Furthermore, the distance between the anode and the glass of the envelope is governed by the conditions of radiation from the anode, i. e. by the power dissipated, which is a function of the area of the anode. Consequently, the diameter D (Fig. 1) of the cylindrical portion of the glass envelope E of the tube, which surrounds the anode A, becomes larger as the maximum diagonal d of the straight section of the anode is increased, i. e. for a given perimeter of the straight section, the anode is of flatter shape.

Such shapes of electrodes as are adopted in the usual thermionic tubes have, therefore, a double drawback. Not only do they fail to provide the conditions necessary for optimum distribution of the electron stream but they also require the use of glass envelopes of unnecessarily large volume.

The present invention has precisely for its object to modify the shape of the electrodes of the tube in such a manner that, while providing an efficient distribution of the electron stream, those portions of the envelope whose presence in the tube is to be explained only by the technical requirements of closing are completely eliminated. In this way a substantial reduction in the overall dimensions of the tube is secured. The said invention is based on the discovery that the substitution, in a discharge tube, of the parallelepipedic anode by a spherical anode of the same area, permits of a considerable reduction (of the order of 40%) in the uselessly high volumetric

content required in a tube envelope housing a parallelepipedic anode.

According to the invention, in addition to the spherical anode, the cathode and all the other electrodes of the tube are also of spherical shape and all electrodes are concentrically and symmetrically mounted on a medial disc of insulating material; finally, the whole arrangement is enclosed in a glass envelope, which is likewise spherical and is concentric with the electrodes, the leads from said electrodes being located in a medial plane of the envelope.

Under these conditions, it is obvious, in view of the symmetrical arrangement that, in the space limited by the cathode and the anode, which are both spherical and concentric, the electron stream is distributed in the most efficient manner.

On the other hand, as regards the dimensioning of the electrodes, it is known that the output power of the tube depends on the area of the cathode and that, from the predetermined values given for the output power and the dissipated power, are deduced the values of the areas of the cathode and of the anode and, consequently, their radii; from the foregoing values the radii of the intermediate electrodes can then be calculated.

By way of a non-limitative example, a description will now be given of a construction according to the invention, this construction being illustrated in the accompanying drawings in which:

Fig. 1 is a diagrammatic view in perspective used to aid in distinguishing the principles of this invention from those of the prior art;

Fig. 2 is a diagrammatic view partly in section of the electrode arrangement according to the invention;

Fig. 3 is an elevational view of the base used for supporting electrodes;

Fig. 4 is a plan view of the electrode arrangement showing the screen dividing the tube along a diametral plane and is taken on lines C—D of Fig. 5;

Fig. 5 shows a sectional elevational view taken on lines A—B of Fig. 4.

A disc of insulating material, I, supports in a central aperture Ia , the spherical cathode C and its internal heating element F. Concentric with the said cathode C and mounted on the same disc I are the grids $G_1, G_2 \dots G_n$, and also the anode A; in the figure, only the first grid G_1 and the last G_n have been shown.

In order to allow the leads from the various electrodes to emerge from the envelope, the disc I comprises in reality, two contiguous discs between which the said leads are held rigidly in

the diametral plane of the tube, before the external spherical envelope is sealed. The said envelope itself is formed by two hemispherical glass capes E, E', which are fixed together edge to edge. The sealing in of the outgoing leads is, on the other hand, effected by hot-pressing between two external nipples, moulded integrally with the two caps E, E', when the tube is being closed.

Apart from the advantage of the reduction in bulk which is obtained by the use of electrodes of spherical shape, the design according to the invention also has the advantage of enabling the manufacture of all the electrodes to be effected by means of simple stamping operations. In this respect, the simplification is particularly noticeable in the manufacture of reticulated grids. Such grids are constructed, in the shape of a cap, from wire gauze; the cap M (Fig. 3) is then provided at its base with a suitable ring R and with an appropriate system of fasteners K, K' enabling the ring to bear accurately against the trued surface of the medial disc I.

It follows, in particular, that, with the design according to the invention, it is possible to ensure extremely accurate assembly of the elements of the discharge tube with reference to the medial disc I, by taking as a datum plane each of the two flat surfaces of said disc.

Finally, owing to the fact that such a tube, according to the invention, comprises two identical parts which are located symmetrically with respect to the double medial support I, there is nothing to prevent the said two parts from being made independent, by separating them by means of an electrostatic screen S interposed between the two insulating discs of the support I. The heater type cathode is connected to the said screen and separate leads are provided for two electrodes of the same denomination. A double tube is thus obtained which can be exactly symmetrical as regards its two halves.

The advantages which accrue from the shape of the electrodes proposed by the invention will obviously have their maximum effect if such shape is exactly spherical. Yet these advantages will still subsist in part if the electrodes, instead of being truly spherical, have the shape of a closed convex surface having at least one plane of symmetry. Of course, the invention also covers thermionic discharge tubes constructed with electrodes of this latter type.

I claim:

1. A spherical electronic discharge tube having a spherical, indirectly heated cathode, other electrodes cooperating therewith, said cooperating electrodes being spherical, concentric with said cathode and each constituted by two identical half-sections mounted on a common, insulated, annular support, means mounting said cathode and support so as to be centered on the cathode, the said support also serving to support rigid, rectilinear connecting leads for the electrodes, and the inner diameter of said annular support being greater than the diameter of the cathode.

2. Electronic discharge tube having a spherical, indirectly heated cathode, other electrodes cooperating therewith, said cooperating electrodes being spherical, concentric with said cathode and each constituted by two identical half-sections mounted on a common insulated, annular support centered on the cathode, the said support also serving to support rigid, rectilinear connecting leads for the electrodes, and the inner

diameter of said annular support being greater than the diameter of the cathode, said tube having a hermetically sealed, spherical envelope, concentric with the cathode and supported in spaced relationship to said electrodes and traversed by said rigid connecting leads.

3. Electronic discharge tube having a spherical, indirectly heated cathode, other electrodes cooperating therewith, said cooperating electrodes being spherical, concentric with said cathode and each constituted by two identical half-sections mounted on a common insulated, annular support centered on the cathode, the said support also serving to support rigid, rectilinear connecting leads for the electrodes, and the inner diameter of said annular support being greater than the diameter of the cathode, said insulating support, having plane parallel surfaces, being constituted by two identical half portions, the contacting surfaces thereof being provided with grooves permitting passage of said rigid connecting leads.

4. Electronic discharge tube having a spherical, indirectly heated cathode, other electrodes cooperating therewith, said cooperating electrodes being spherical, concentric with said cathode and each constituted by two identical half-sections mounted on a common insulated, annular support centered on the cathode, the said support also serving to support rigid, rectilinear connecting leads for the electrodes, and the inner diameter of said annular support being greater than the diameter of the cathode, the two identical half-sections of each electrode being individually surrounded by an annular base, said base being provided with metal tongues, and corresponding slots in said support adapted to receive said tongues and to support said base.

5. Electronic discharge tube having a spherical, indirectly heated cathode, other electrodes cooperating therewith, said cooperating electrodes being spherical, concentric with said cathode and each constituted by two identical half-sections mounted on a common insulated, annular support centered on the cathode, the said support also serving to support rigid, rectilinear connecting leads for the electrodes, and the inner diameter of said annular support being greater than the diameter of the cathode, said tube having a hermetically sealed, spherical envelope, concentric with the cathode and constituted by two identical, hemispherical segments, the contacting edges of said segments being beaded and traversed by said rigid connecting leads.

6. Electronic discharge tube having a spherical, indirectly heated cathode, wherein the electrodes cooperating with the cathode are spherical, concentric therewith and each constituted by two identical half-sections mounted on a common, insulated, annular support centered on the cathode, said support comprising a metal annulus having both plane surfaces covered with a uniformly thick insulating material, the said support also serving to support rigid, rectilinear connecting leads for the electrodes, and the inner diameter of said annular support being greater than the diameter of the cathode.

7. Electronic discharge tube according to claim 6 wherein the said metal annulus is connected to the cathode by at least three radial tongues spaced evenly around the inner edge of said annulus.

8. Electronic discharge tube according to claim 6 having a hermetically sealed, spherical envelope, concentric with the cathode and con-

nnected to said annulus by said rigid connecting leads, said leads being located in the median plane of said annulus.

9. In an electronic discharge tube bounded by a gas-tight spherical envelope of two parts united by junction flanges, an indirectly heated spherical cathode concentric with the envelope, electrodes likewise spherical enveloping said cathode, concentric with the latter and constituted individually by two identical halves, means enabling external connections of the cathode, its heating circuit and the two halves of each enveloping electrode, said means comprising at least two annular insulating disks of like contour with plane and parallel faces superposed one on the other and having interior diameters larger than that of the cathode, and centered on said cathode together with means comprising at least three projections for connecting said disks and cathode, rigid conductors radially connected to the electrodes, fixed in one of the faces of the

two disks and traversing the envelope entirely in the same diametral plane in the region of the flanged junction of the two parts of said envelope.
